PAPER BAG RACK

Woodrow W. Reeser, 853 E. Broad St., Elyria, Ohio

Filed Sept. 11, 1962, Ser. No. 71,654

Term of patent 3½ years

(Cl. D80—10)

Fig. 1

Fig. 2

Fig. 3

Fig. 4

FIG. 1 is a perspective view of a paper bag rack, showing my new design;

FIG. 2 is a rear elevational view;

FIG. 3 is a side elevational view; and

FIG. 4 is a top plan view.

I claim:

The ornamental design for a paper bag rack, as shown.
